CLAIM

The ornamental design for a brush handle, as shown and described.

DESCRIPTION

FIG. 1 is a rear, right and top perspective view of a brush handle, showing my design.

FIG. 2 is a front, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right and top perspective view of the brush handle in a usable state.

The broken lines shown in FIGS. 1, 2, 5, 6 are included for the purpose of illustrating portions of the brush handle that form no part of the claimed design. The broken lines shown in FIG. 9 are included for the purpose of illustrating environmental structure and forms no part of the claimed design.

1 Claim, 9 Drawing Sheets
